UNITED STATES PATENT OFFICE.

AUSTIN KIMBLE, OF WAUSAU, WISCONSIN, ASSIGNOR TO MARATHON ELECTRIC MFG. COMPANY, OF WAUSAU, WISCONSIN, A CORPORATION OF WISCONSIN.

CENTRIFUGAL GOVERNOR.

1,357,403

Specification of Letters Patent.

Patented Nov. 2, 1920.

Application filed October 21, 1918. Serial No. 259,086.

To all whom it may concern:

Be it known that I, AUSTIN KIMBLE, a citizen of the United States of America, and a resident of Wausau, county of Marathon, 5 and State of Wisconsin, have invented certain new and useful Improvements in Centrifugal Governors, of which the following is a specification.

This invention relates to automatic governors of the centrifugal type, adapted for instance to control a switch, clutch, valve or other mechanism, and more particularly it relates to electric motors of the split-phase induction type having automatic means for 15 cutting out the auxiliary field winding, depending on the speed of the rotor.

The main objects of this invention are to provide automatic switching means of improved form and operation adapted to control the auxiliary field circuit of a split-phase induction motor; to provide for such a motor governing means responsive to speed variations and adapted to operate in one direction to open the circuit at a certain 25 speed as the speed increases, as in starting, and to close the circuit at a certain lower speed as the velocity decreases; to provide in such a device a switch in combination with a centrifugal governor therefor including a resilient part adapted for actuation outward by centrifugal force when the rotor comes up to a certain speed and adapted to retain its outward or expanded position until the speed of the rotor has diminished to 30 a point substantially below that at which the governor is initially actuated; and to provide a centrifugally operable expansible annulus governor adapted to operate one way at one speed and to reverse at a different 35 speed.

An illustrative embodiment of this invention is shown in the accompanying drawings, in which—

Figure 1 is a side elevation of the governor and that end of the rotor on which it is mounted, and shows also that switch contact which is carried by the governor.

Fig. 2 is a section on the line 3—3 of Fig. 1.

Fig. 3 is a section on the line 3—3 of Fig. 2, and also includes part of the stationary frame.

Fig. 4 is also a section on the line 3—3 of Fig. 2, but with the governor expanded.

Fig. 5 is a conventional circuit diagram 55 showing the relation of the governor to the switch and its effect on field excitation.

In the illustrative embodiment shown in the drawings, such parts only of a split-phase induction motor are included as are 60 considered necessary for explaining the invention. Referring to said drawings, the rotor 1 is of the squirrel-cage type and comprises a laminated core 2 fixed on the shaft 3, as usual in induction motors.

The stator or field member is provided with a main winding 4 and an auxiliary winding or teaser 5 disposed at an angle thereto and designed to act as a starting coil, as understood in the art and as customary 70 in split-phase motors, a switch 6 being provided for cutting out the winding 5 under normal running conditions, subject to automatic control by a governor 7 according to speed, as hereinafter described.

The governor 7 is mounted on said shaft 3 adjacent to said core 2, being preferably spaced somewhat from the copper end-ring 8 and adjacent tips of the interconnected hollow bars 9 constituting the squirrel cage 80 member, so as to avoid interfering materially with the ventilating draft through the conductor flues 10, which flues may be substantially like those described in my co-pending application, Serial No. 235,247, filed 85 May 18, 1918.

The general shape of the main body of said governor 7 is discoidal, and the outer edge is to advantage substantially flush with the cylindrical face of the core 2. Said 90 governor comprises a centrifugally responsive member 11 in the form of an endless helical spring of annulus shape, in combination with a pair of conoidal guides or retainers 12 and 13 disposed with their 95 convex faces toward each other, one being fixed relative to the shaft 3 and the other being slidable lengthwise of said shaft, and resilient means 14 urging said retainers toward each other against the yielding opposition of said spring 11, which is wedgely 100 embraced slidably between them. Said means 14 is in the form of a helical spring the loops of which are substantially con-

centric with said shaft. Said spring 14 is arranged in compression between the outer side of the slidable member 13 and a stop-ring on shoulder 15 which is substantially 5 rigid with said shaft. The helical spring member 11 is free of positive connection to the rest of the governor and may be said to be in floating relation thereto.

The switch 6 includes a substantially 10 stationary contact 16 carried by the frame or housing 17 and a rotary contact member 18 of ring-shape carried by the axially slid- able member 13 of the governor, in such relation that operation of the governor in 15 one direction, as in speeding up, serves to open the switch, and vice versa. Said switch also includes another stationary contact 19 similar to 16 also arranged to coact with the ring 18 in like manner, said con- 20 tacts being disposed preferably on oppo- site sides of the shaft 3, and each being supported somewhat yieldingly on resilient conductor arms 20 which in turn are se- cured to an insulating block 21 fixed on said 25 frame 17 at one side of shaft 3. Said switch is connected in series with the starting cir- 30 circuit by means of the leads 22 and 23 at- tached to the arms 20 respectively. Said arms 20 are preferably made in the form of leaf springs, and the contact blocks 16 and 19, preferably made of carbon, which bear on the switch-ring 18 may to advantage be fastened in place interchangeably on said arms, as by screws 24, so as to facilitate 35 renewal.

The inner member or plate 12 of said 40 governor is adapted for stamping from sheet metal and comprises a flat middle part perforated centrally to receive the shaft 3. The outer part of said plate flares conoidally at 25 toward the core 2 and terminates peripherally in a series of spaced teeth 26 turned abruptly in the opposite direction and disposed nearly parallel with the shaft. 45 The inner part of said plate fits against an outwardly facing shoulder 27 on said shaft and is thereby held in definite spaced relation to the core 2. The complementary gov- 50 ernor guide member 13 includes a plate 28 substantially similar to plate 12 but facing oppositely so that their respective flares at 25 and 29 are mutually divergent. The teeth 30 on plate 28 are adapted to interfit with and lap past the teeth 26 of plate 12 when 55 the governor is at rest and contracted. When the governor is expanded, the tips of all of said teeth come substantially into circular alinement and the teeth as a whole constitute a kind of barred cage or peri- 60 pheral retainer which serves to limit the radial expansion of the resilient annulus 11 when the rotor comes up to speed. The inner part of plate 28 adjacent to its per- 65 foration for the shaft 3 is secured, prefer- ably in a rigid manner, to one end of a

sleeve 31. The opposite end of said sleeve is secured to a radially disposed disk 32 also perforated to receive said shaft. Said disk 32 is preferably of insulating material and serves to support the switch-ring 18 in op- 70 erative relation to the stationary contacts 16 and 19 whenever it is moved into its run- ning position. Said ring 18, disk 32, and sleeve 31 are substantially parts of the axi- ally movable member 13 of the governor 75 7 and hence responsive to the centrifugally induced movements of the spring 11.

In starting the motor by closing the cur- 80 rent supply switch 33, the operation of the device is as follows: Initially the governing annulus 11 is contracted so that the plates 12 and 18 are forced apart and the switch is closed and both field windings are effective, but as the rotor speeds up, centrifugal force operates to gradually expand said an- 85 nulus. As soon as said annulus recedes out- 90 ward sufficiently over the conoidal faces of walls 25 and 29, the slidable member 13 is thereby released and is moved by spring 14 away from the stationary switch contacts 95 16 and 19 and the switch 6 is thereby opened and the auxiliary winding cut out. Further expansion of said annulus brings it against the stop-teeth 20 and 30, where it remains until for any reason, such for 95 instance as overload or open circuit, the rotor speed diminishes substantially below that at which the switch was opened. The tension of the annulus spring then over- 100 comes both the reduced centrifugal force and the opposition of spring 11, as well as friction, and pulls itself wedgingly inward between said members 12 and 13 and so, 105 forcing the latter outward, serves to close the switch 6 at contacts 16 and 19. Then unless the main switch 33 has been opened the motor will again operate as a split- 110 phase machine and so carry the extra load, and speed up again to normal, as soon as the load will permit.

In stopping the motor upon opening the power supply switch 33, the speed will im- 115 mediately fall gradually, thus permitting the annulus 11 to contract and so close the auxiliary field control switch 6 ready for starting again, though such reverse opera- 120 tion of the governor and switch occurs at a substantially lower speed than required for their operation in speeding up.

This characteristic speed interval feature 120 of the governor herein described is highly advantageous for induction motors operating under variable loads and where constant speed is not necessary, and especially where there are frequent overloads, because in such 125 machines the auxiliary winding is ordinarily very inefficient respecting its consumption of power and should be thrown in only on such overloads as are sufficient to slow down the speed very materially, whereas in start- 130

ing the motor said winding should be permitted to remain in circuit until the rotor has acquired approximately full speed. The speed interval between the cut-out speed in 5 speeding up and the lower cut-in speed in slowing down depends on several factors in design, as for instance the relative length and stiffness of the annulus 11, the resiliency of spring 14, and the conical pitch of the 10 members 12 and 13.

Although but one specific embodiment of this invention has been herein shown and described, it will be understood that numerous details of the construction shown may be altered or omitted without departing from the 15 spirit of this invention as defined by the following claims.

I claim:

1. In a centrifugal governor, a yielding 20 annulus resiliently expansible peripherally at a certain speed by centrifugal force acting on its own mass, and guide means therefor mechanically responsive to the movement of said annulus, said means including inner and 25 outer parts bearing yieldingly against said annulus and having fixed radial distances from the common axis, one of said parts including a switch controlling member, and said annulus being movable between said 30 parts, whereby the switch actuating part is effectually controlled.

2. A centrifugal governor including a part 35 expansible by centrifugal force at a certain speed and operatively contractible solely at a substantially lower speed, said part being in the form of a resilient annulus disposed coaxially with the governor, and a

conoidal body also disposed coaxially with the governor in coactive relation to said part for relative axial movement. 40

3. A centrifugal governor comprising a shaft, a pair of conoidal retainer guides mounted coaxially on said shaft with their convex sides facing toward each other and one of them being slideable axially, means 45 urging said guides together, and a centrifugally expansible annulus disposed between said guides in operative relation to said sides.

4. A centrifugal governor comprising a 50 shaft, a pair of conoidal retainer guides mounted coaxially on said shaft with their convex sides facing toward each other and one of them being slideable axially, means urging said guides together, and a centrifugally expansible annulus disposed between 55 said guides in operative relation to said sides, said guides having their outer edges turned reversely and toward each other and said edges being formed with alternate teeth 60 and notches whereby said edges may interfit and so serve as a peripheral expansion stop for said annulus.

5. A centrifugal governor comprising a 65 shaft, a pair of guides facing each other on said shaft, and a centrifugally responsive member disposed between said guides in operative wedging relation thereto, said guides having relatively flaring adjacent faces, and one of said guides being movable axially. 70

Signed at Wausau, Wis., this 18th day of October, 1918.

AUSTIN KIMBLE.
